UNITED STATES PATENT OFFICE.

GEORGE J. RICHARDSON, OF PETERSBURG, VIRGINIA, ASSIGNOR TO AMERICAN SPOT-LESS STREET SYSTEM, INC., OF PETERSBURG, VIRGINIA, A CORPORATION OF VIRGINIA.

COMBINED TRASH RECEPTACLE AND ADVERTISING CARRIER.

1,424,519.

Specification of Letters Patent. Patented Aug. 1, 1922.

Application filed June 30, 1920. Serial No. 392,988.

To all whom it may concern:

Be it known that I, GEORGE J. RICHARDSON, a citizen of the United States of America, residing at Petersburg, in the county of Dinwiddie and State of Virginia, have invented certain new and useful Improvements in Combined Trash Receptacles and Advertising Carriers, of which the following is a specification.

10 This invention relates to a combined trash receptacle and advertising carrier, wherein the receptacle is specifically constructed as complete for a trash receptacle and provided for the removable reception of advertising sections.

15 The improved combined trash receptacle and advertising carrier is further constructed for the reception of a flexible retainer, such as a bag, into which the trash 20 is delivered while the bag is held open within the receptacle, the top of the receptacle being constructed for hinge connection with the receptacle proper, and being formed with a plurality of doors, particularly located so that they may be readily turned to open position to provide for a direct entrance of the trash into the bag.

In the drawings:

25 Fig. 1 is a perspective view of the improved trash receptacle and advertising carrier.

30 Fig. 2 is a similar view with the top open, showing the bag in distended relation.

35 Fig. 3 is a broken side elevation of the receptacle showing the bag with the mouth closed and partly withdrawn from the receptacle.

Fig. 4 is a section on line 4—4 of Fig. 3.

40 Fig. 5 is a broken vertical section, illustrating particularly the operative relation of the doors and the openings covered thereby and through which the trash is delivered to the bag.

45 In the drawings, the improved receptacle is shown as comprising a body 1, of approximately rectangular form including walls 2 secured together by exterior corner braces 3. Overlying and secured to the braces 3 are angular corner pieces 4 which extend 50 beyond the edges of the braces 3, and thereby provide between the extended portions of said corner pieces and the walls of the receptacle, channels or grooves 5 into which may be readily inserted advertising

slides 6 the latter being supported at the bottom by suitable means, such for instance as shown at 6^a. The corner braces may if desired, have upper and lower strips 7 and 8, which by the spacing referred to, additionally guide and overlie the advertising strips 6 when the latter are in position.

The receptacle is supported upon legs 9, and is provided at the upper open end with a cover 10, the walls of which form the lower margin which is commensurate in size and shape with the top of the receptacle, curve upwardly and inwardly at 11, and terminate in a centrally located upstanding rectangular section 12, the edge walls of which are in a plane substantially parallel to the walls of the receptacle, as at 13. The upwardly and inwardly curved walls 11 are formed with openings 14, and doors 15 are hinged to the walls to cover said openings.

75 The cover 10 is hinged at 16 to the upper edge of the receptacle proper, and the lower edge of the cover, when said cover is closed, bears upon and overlies the upper edges of the advertising slides 6. Therefore when the cover is locked in closed position, as through means 17, the slides are fixed against possibility of movement in the receptacle. Limiting straps 18 connect the cover and receptacle to prevent undue opening movement of the cover, and when it is desired to insert panels, the straps 18 are released, so that the cover can be thrown back.

80 A flexible container such as the bag 19 is adapted to be used within the receptacle for the reception of trash, and the receptacle is provided with hooks or other supports 20 within the upper edge thereof, on which the mouth edge of the bag may be secured to hold the bag in open position.

85 It will be noted that with the bag held in such position, the edges of the bag are adjacent the walls of the receptacle, and that due to the inward curve of the walls 100 of the cover in which the trash admission openings are formed, all trash delivered through said openings is prevented from falling into any portion of the receptacle other than the bag. In other words, the 105 relation of the openings 14 are such that all material delivered therethrough is compelled to fall into the bag.

22
After the bag has been filled, the mouth edge thereof is disengaged from the receptacle, closed and secured by a retainer as 21 and bodily removed from the receptacle.

5 The upright edges 13 of the section 12 of the cover provide an efficient space for appropriate lettering such as the street designation, or the like.

What I claim is:—

- 10 A combined trash and advertising medium comprising a receptacle, a skeleton frame spaced from the walls of and surrounding the receptacle to form panel guideways, panels fitted in the guideways, 15 a cover hinged to the top of the frame outside the vertical plane of the guideways, whereby to permit of removal of the panels when the cover is in open position or when closed to hold said panels against move-

ment, said cover having upwardly and inwardly curved walls terminating in a square dome having vertical side walls to receive advertising data, one of the upwardly and inwardly curved walls having an opening, the uppermost wall of which is spaced from the adjacent vertical wall of the dome, a closure hinged to said upper wall and curved in cross-section to substantially correspond to the curvature of the curved wall in which the opening is formed, 30 whereby when the closure is thrown open it will be supported in an inclined position against the dome and a substantially curved chute is formed to direct trash into the opening.

35 In testimony whereof I affix my signature.

GEORGE J. RICHARDSON.
